METAL DIAPHRAGM FOR CAR-VESTIBULES.

1,211,654.

Specification of Letters Patent.

Patented Jan. 9, 1917.

Application filed July 15, 1914, Serial No. 851,034. Renewed November 24, 1916. Serial No. 133,267.

To all whom it may concern:

Be it known that we, THOMAS W. YOUNGER and OTTO B. SCHOENKY, citizens of the United States, and residents of the city of Sacramento, in the county of Sacramento and State of California, have invented a new and useful Improvement in Metal Diaphragms for Car-Vestibules, of which the following is a specification.

10 Our invention relates to diaphragms for the vestibules of railway passenger cars.

One of the principal objects of our invention is to provide a diaphragm for car vestibules which is cheap and durable and 15 which is not liable to be injured while in service.

Further objects are to attain certain advantages as will appear more fully hereinafter.

20 The invention consists in two arched metal plates which are secured to the frame of a car and to the vestibule face plate respectively, and which fit telescopically together to form a tight joint, while permitting a 25 movement of the vestibule face plate to and from the frame of the car.

In the accompanying drawing, which forms part of this specification, and in which like reference characters refer to like 30 parts throughout the several views, Figure 1 is a fragmentary view of the vestibule of a passenger car with a diaphragm embodying my invention applied thereto, the left-hand half of said Fig. 1 being an end elevation showing the vestibule face plate, and the right-hand half of said Fig. 1 being a 35 vertical section through the diaphragm; Fig. 2 is a fragmentary vertical longitudinal section through the middle of the vestibule 40 of a passenger car showing the diaphragm applied thereto; Fig. 3 is a fragmentary top view of the vestibule of a passenger car, the left-hand half of said Fig. 3 being a plan showing the vestibule face plate and dia-

45 phragm, the roof of the car being removed; and the right-hand half of said Fig. 3 being a horizontal section through the vestibule face plate and diaphragm, with parts of the floor of the vestibule and of the buffer plate 50 broken away; Fig. 4 is an enlarged fragmentary horizontal section on the line 4—4 of Fig. 2; Fig. 5 is a fragmentary vertical section through the vestibule face plate and diaphragm.

55 In the construction of vestibules of rail-

way passenger cars, to which a diaphragm embodying the invention is shown as applied, a vestibule face plate 1, constituting an arched doorway, is secured at its lower ends to a buffer plate 2. The buffer plate 2 60 is supported by two side buffer stems 3 which are guided horizontally in the platform end sill 4 of the car frame. The side buffer stems 3 are pivotally connected to the buffer plate 2 and are pressed outwardly from the 65 car by side buffer springs 5. Engaging the buffer plate 2 is a center buffer stem 6 which is pressed outwardly from the car by center buffer springs 7. The upper part of the vestibule face plate 1 is pressed outwardly 70 from the car by two buffer stems 8 and corresponding buffer springs 9. A foot plate 10 is secured to the floor of the platform of the car and projects over the buffer plate 2.

The diaphragm for the vestibule comprises 75 a metal plate 11 which is arched or curved in an inverted U shape. One edge portion of the plate 11 is bent at right angles to said plate and is fastened by screws 12 or other suitable means to the door frame 13 of the 80 doorway in the outer wall of the platform of the car. Coöoperating with the plate 11 is another metal plate 14, one edge portion of which is bent at right angles to said plate 14, and fastened by screws 15 or other suitable means to the vestibule face plate 1. One of the plates 11 and 14, preferably the outer plate 14, fits telescopically within the other plate. The free edge portion of each of the plates 11 and 14 has a rebend 16 which 90 contacts with the other plate. In the upper face of the outer plate 14 is a water groove 17 which extends across the arched top of said outer plate, preferably near the outer edge of the other plate 11, when said plates 95 are in their normal position. A curtain 8 is arranged to be extended across the inside faces of the upright portions of the plates 11 and 14 in the usual way.

As the vestibule face plate 1 moves back 100 and forth relative to the car, the plates 11 and 14 slide on each other to permit such movement of the vestibule face plate, while maintaining a tight joint between said plates. The plates 11 and 14 may be made of any 105 kind of metal, but are preferably thin steel plates which are slightly resilient. Since the diaphragm is made of metal plates, it cannot be easily injured, either maliciously by tramps, or accidentally; nor can it be burned 110

by hot cinders. A diaphragm of metal plates will be more durable and will withstand the weather better than the cloth diaphragm now generally used. The water groove 17 5 guides the water sidewise from the outer plate 14 instead of against the joint between the plates 14 and 11.

While a diaphragm embodying the invention has been shown applied to the usual 10 vestibule construction, it is not limited in use to this construction. The plate 11 and the plate 14 may each be made of separate plates, if desired, instead of one plate, as shown and described. Other changes may 15 be made in the particular construction which is shown and described without departing from our invention and we do not wish to

be limited to the details of this particular construction.

What we claim is:

A diaphragm for car vestibules comprising two arched plates fitting together telescopically and adapted to be secured between the vestibule face plate and the frame of a car, the outer plate having a water groove 25 in the upper face of its arched portion.

Signed at Sacramento, California, this 8th day of July, 1914.

THOMAS W. YOUNGER.
OTTO B. SCHOENKY.
